UNITED STATES PATENT OFFICE.

WALTER M. TIETZ, OF NEWARK, NEW JERSEY.

RAZOR-BLADE HOLDER.

Application filed August 3, 1925, Serial No. 47,803. Renewed March 8, 1927.

This invention relates more particularly to a class of sharpening devices.

My invention has for its object primarily to provide a device designed to be employed for removably holding especially safety razor blades in a manner for being sharpened whereby the person when accomplishing the sharpening process will not risk the danger of being cut as well as permitting the blades to be effectually whetted and honed without liability of damaging a strop, and which is of a form that serves to enable the blades when sharpened to be removed without requiring the usual handling as is incident to the operation of many types of devices of this class. The invention resides mainly in the provision of a tubular handle having extending from one of its ends on approximately a similar relative plane a fixed jaw member or strip for supporting a razor blade, and slidable on the fixed jaw member is a second jaw member or strip for clamping the razor blade. On the slidable jaw member are clips or hooks which engage the fixed jaw member for loosely holding the slidable jaw member in movable position on the fixed jaw member, and the slidable jaw member may have a stem which is movable in the tubular member for permitting the slidable member to be manually moved upon and from the fixed member.

A further object of the invention is to provide a razor blade holder of a simple, efficient and durable construction which may be made in appropriate sizes and shapes.

With these and other objects in view, the invention will be hereinafter more fully explained with reference to the accompanying drawing forming a part of this specification in which similar characters of reference indicate corresponding parts in all the views, and will then be pointed out in the claim at the end of the description.

In the drawing, Figure 1 is a plan of one form of razor blade holder embodying my invention.

Fig. 2 is a sectional view taken longitudinally through the device.

Fig. 3 is a fragmentary view, showing partly in elevation and partly in section the device with one of its jaw members extensiblly adjusted.

Fig. 4 is an enlarged sectional view taken on the line 4-4 of Fig. 2 with a razor blade arranged between the jaw members.

Fig. 5 is an enlarged sectional view taken on the line 5-5 of Fig. 3.

Fig. 6 is a plan of one form of razor blade adapted to be sharpened by the use of the device, and

Fig. 7 is a plan of another form of safety razor blade.

The device or holder has a handle 10 which is preferably tubular in form of a suitable diameter and length to permit of being conveniently held in the hand of a person, and when made of sheet metal one end of the handle may be bent so as to close the end. The second end of the handle is open, as at 11, and in part of the handle is a slot 12 which extends lengthwise of the handle for a suitable distance with one of its ends terminating in proximity to the open end 11 of the handle. The part of the handle between its open end and the adjacent end of the slot 12 provides a stop, as 13.

Extending from the part of the open end 11 of the handle opposite to the slot 12 is a fixed jaw member 14, and this jaw member is in the form of a rigid strip of metal preferably of an elongated substantially rectangular shape of a length suitable to accommodate and support thereon any of the commonly used forms of safety razor blades. In the central part of the face of the jaw member or strip 14 in opposed relation to the slot 12 may be a groove 15 extending throughout the length of the member for receiving therein the rib or flange, as A, of a well known form of razor blade, as B.

On the groove face of the jaw member 14 is a slidable jaw member 16 which is also preferably made of a rigid strip of spring metal of a size and shape similar to the size and shape of the jaw member 14 for clamping a razor blade between the members. In the central part of the face of the jaw member or strip 16 opposed to the jaw member 14 may be a groove 17 extending throughout its length, and the groove 17 communicates with the groove 15 of the jaw member 14 for also receiving the rib A of the razor blade B. Protruding from the end of the slidable jaw member 16 is a stem or rod 18 which is slidably movable inwardly and outwardly of the handle through its open end. The stem 18 may be substantially semi-circular in cross section to provide a flat lengthwise face 19 so that when the stem is moved outwardly of the handle its flat face will

move close upon the grooved face of the jaw member 14. Projecting outwardly of the slot 12 of the handle from the end of the stem 18 opposite to the jaw member 16 is a head or knob, as 20, for permitting the stem and the jaw member 16 to be slidably moved within the handle and upon the jaw member 14 by a finger of the person manipulating the device. The knob 20 is so positioned on the stem 18 that when the stem is moved outwardly of the handle for a distance to move the jaw member 16 almost beyond the free end of the jaw member 14 the knob will contact with the stop 13 of the handle for preventing the jaw member from further movement and to prevent the stem 18 from moving entirely out of the handle. On opposite parts of the side edges of the jaw member 16 adjacent the stem 18 are two clips or hooks 21, 22 which are bent over in movable engagement on the side edges of the rigid jaw member 14 for holding the jaw members in relative closely spaced positions so that the razor blades may be accommodated therebetween.

On the slidable jaw member 16 may also be one or two spaced corresponding yielding clamps or ejectors, as 23, 23^a, for serving to hold the blades between the jaw members, and each of these ejectors is in the form of a spring finger which may be struck out of the bottom of the groove 17 of this member so that one of its ends is free. Both of the spring fingers are disposed on alignment lengthwise of the groove on inclines outwardly of the groove with their free ends protruding toward the free end of the slid- able jaw member, and on the free end of each finger may be a head or enlargement 24. The spring fingers 23, 23^a are also of lengths that when a form of razor blade, as C, having spaced holes, as D, is positioned between the jaw members the heads 24 of the fingers will engage one or two of the holes of the blade, or when the form of the razor blade B is between the jaw members the heads 24 of the spring fingers will clamp the blade by engaging the rib A of the blade.

The device is employed for sharpening razor blades by moving the knob 20 for moving the stem 18 outwardly of the handle to adjust the slidable jaw member 16 its maximum distance beyond the free end of

the jaw member 14. The razor blade is then arranged on the slidable jaw member 16 over its fingers or clamps or ejectors 23, 23^a, and the slidable jaw member with the stem 18 and knob 20 are reversely moved to cause the blade to be removably clamped between both jaw members. The holder is manipulated for sharpening the blade in usual manner, and afterward by moving the knob 20, stem 18 and the jaw member 16 outwardly from the handle 10, as above explained, the heads 24 of the fingers 23, 23^a will engage and carry the blade along with the jaw member 16. The blade may then be removed from this jaw member without danger of the person being cut.

In the foregoing description, I have embodied the preferred form of my invention, but I do not wish to be understood as limiting myself thereto, as I am aware that modifications may be made therein without departing from the principle or sacrificing any of the advantages of this invention, therefore, I reserve to myself the right to make such changes as fairly fall within the scope thereof.

Having thus described my invention, I claim as new and desire to secure by Letters Patent:—

A razor blade holder, comprising a tubular handle having extending on approximately a similar relative plane from one of its ends a fixed rigid strip member for supporting the razor blade, a second strip slid- able on the fixed strip member for clamping the razor blade, hooks on the side edges of the slidable strip member overlapping the side edges of the fixed strip member for loosely holding the slidable strip member in movable contact with the fixed strip member, two spring fingers protruding outwardly of the groove of the slidable strip member, each finger having an unattached end with a head for engaging and carrying the razor blade with the slidable strip member when moved from contact with the fixed strip member, and a stem on the slid- able strip movable inwardly and outwardly of the tubular handle for moving the slid- able strip and its finger.

This specification signed this 1st day of August, A. D. 1925.

WALTER M. TIETZ.
